UNITED STATES PATENT OFFICE.

FRED C. BAUER, OF IRVINGTON, NEW JERSEY, ASSIGNOR TO BAUER DEVICES INC.,
A CORPORATION OF NEW YORK.

CONTACT-MAKING DEVICE.

Application filed August 13, 1925. Serial No. 49,944.

This invention is designed to provide a device for successively spelling out letters or words on electric signs or to produce other lighting effects in succession, the device being compact and having a series of lighting contacts which are fixed and which are placed in contact with a liquid in a receptacle, the height of the liquid being controlled by a magnetically operated mechanism.

The invention also resides in certain details of construction which will be herein-after more fully described and finally embodied in the claims.

The invention is illustrated in the accompanying drawings in which Figure 1 is a front view of the device with the magnet and the receptacle shown in section. Figure 2 is a detail view of the cam and its connection with the end of the stem that supports the plunger. Figure 3 is a top view of the device shown in Figure 1. Figure 4 is a section on line 4-4 in Figure 1 and Figure 5 is a diagrammatic view of the electrical circuits as they are attached to the device.

The device is illustrated as mounted on a support comprising a base 10 and an upright 11. The magnet 12 is the means of operation and is controlled by a make and break device which comprises a contact 13 and a pivoted arm 14 which arm has one end 15 to engage the contact and the other end bifurcated to form two projections 16 and 17. The electrical connections in this circuit will be evident from an inspection of Figure 5.

The magnet 12, when energized, pulls up on the rod 18 and this rod acts on the lever 19 and this lever is hinged at one end to the support and at the other end to the arm 20.

On the lever 19 is a pin 21 which is under the piston 22 of the cylinder 23. The cylinder has a check valve 24 at the top and a small hole 25 is disposed at the proper place to act as a vent. When the piston is snapped up the flange 26 hits the point 16 and breaks the contact between the end 15 of the lever and the contact 13. The arm 14 fits tight enough on its pivot to remain in any position in which it is at rest. The piston is heavy enough to positively descend and descends slowly because of the reduction of pressure at its upper end until its

upper end clears the vent 25 and then it drops quickly and strikes the end 17 of the arm 14 and forces the end 15 of the arm into contact with the contact 13 and closes the magnet circuit. This again energizes the magnet, the rod 18 is pushed quickly upward and the operation is repeated.

The contact making mechanism is arranged in the lighting circuit and comprises a receptacle 27 which has the contact rods 28 suspended in it usually by securing their upper ends to the lid 29, the upper ends of the contact rods forming binding posts 30. In the receptacle 27 is a quantity of mercury 31^a, deep enough to contact at all times with one of the contact arms 28. The other arms 28 are of various lengths and disposed so as to be successively placed in circuit as required by raising the level of the mercury.

This is done by a plunger 31 of large area and suspended on the end of a stem 32. The end of the stem is engaged by a cam 33 which is operated by a ratchet 34 and a pawl 35. The pawl 35 is secured on a lever 36 pivoted to swing freely on a post 37 which also supports the cam and is connected by a pin 38 with the lever 19. A pawl 39 prevents backward movement of the cam.

It will be seen that I have thus devised a step-by-step movement to have the cam 33 push down to force the plunger 31 lower and lower to force the level of the mercury upward and thus successively or selectively put the contacts 28 in circuit. These contacts, of course, are electrically connected to such elements as are to be lighted or otherwise actuated. The diagram in Figure 5 shows how these contacts can be arranged, one of them being always in the mercury. When all the contacts have been reached by the mercury, the high point of the cam passes beyond the stem and the float rises and the level of the mercury returns to its lowest point.

To give the greatest possible area to the plunger or float 31, I provide it with grooves 40 in which the contacts 28 are disposed.

I claim:

1. In a contact making device, a receptacle containing a fluid contact material, a plunger in the receptacle and having grooves in its sides, contacts arranged in said grooves, a lid on the receptacle to act as a bearing for the plunger and as a supporter of the contacts.

2. A contact making device comprising a support, a receptacle and a magnet placed side by side on the support, a lever and an arm opposed thereto, both pivoted to the support and in pivotal connection, a rod in the magnet and secured to the lever; a set of contacts in the receptacle and near the edge, a plunger in the receptacle with grooves to receive the contacts, mercury in

the receptacle, a connection for moving the plunger from the arm; a make and break device for energizing the magnet, a cylinder above the lever, and a piston in the cylinder to open the said make and break device when it is raised by the lever and to close the said device when it descends.

In testimony whereof I affix my signature.
FRED C. BAUER.
